UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE-DRUM HOIST.

Application filed June 30, 1925. Serial No. 40,482.

To all whom it may concern:

Be it known that I, EARL B. LEAR, a citizen of the United States, and a resident of Phillipsburg, in the county of Warren and State of New Jersey, have invented a certain Double-Drum Hoist, of which the following is a specification, accompanied by drawings.

This invention relates to double drum hoists, but more particularly to a hoist of the type in which two relatively rotatable drums may be alternately driven from a reversible source of power by automatic clutch mechanism adapted to connect one drum driver or the other to a main reversible drum driver or driving head.

The objects of the present invention are to enable the drums to be placed close together, side by side and permit a double ended pawl to be located opposite the end face of one drum and mounted to rock or swing about an axis transverse to the longitudinal axis of the hoist. For this purpose, the drum drivers are both located at one end 25 of the hoist and the pawl may swing into engagement with one drum driver or the other.

Another object of the invention is to keep the length of the hoist as short as possible 30 while carrying out the construction described and for this purpose the drum drivers are preferably concentric or one outside of the other while the double ended rocking pawl is pivoted between the drum drivers so that the engaging ends of the pawl may swing into engagement with one drum driver or the other. By locating the pawl so that the direction of length of the pawl is substantially at right angles to the longitudinal axis 35 of the machine, the parts may be assembled in reduced longitudinal space and efficient operation is obtained without lengthening the hoist.

The invention is shown in one of its preferred forms in the accompanying drawings, in which—

Figure 1 is a longitudinal sectional elevation of the hoist,

Figure 2 is a detail transverse sectional view partly broken away on the line 2—2 of Figure 1 looking in the direction of the arrows,

Figure 3 is a detail horizontal sectional view taken on the line 3—3 of Figure 2 looking in the direction of the arrows, and

Figure 4 is a detail perspective view of the pawl.

Referring to the drawings, the main frame A is provided with a side frame or standard B at one end and another side frame or standard C at the opposite end which in this instance forms a part of the driving motor of the reversible type. The motor need not be described in detail, but is of the well known flat piston type sometimes called the Dake motor. It will be sufficient to state that by means of such a motor or any other suitable type of motor, the main driving shaft D is rotated by imparting rotation to the crank E having the crank pin F. The motor has a cover G containing a suitable throttle valve for compressed air or other motive fluid controlled by the throttle handle H. The cover G and cylinder frame C are bolted to the center bearing J of the hoist by means of the bolts K. The opposite end of the center bearing J is mounted in the end frame or standard B and this center bearing carries the ball bearings L and O for the main driving shaft D.

The drum P is provided with the bearing sleeve Q rotatable upon the center bearing J and the drum R is rotatable on the extension S of the drum P and is provided with the bearing sleeve T.

The drum P is provided with the drum driver U secured thereto as by means of the bolts V and the drum R is provided with the drum driver W secured thereto by means of the bolts or rivets X. These two drum drivers may be in the form of rings having oppositely facing teeth Y and Z respectively.

The main driver, in this instance, comprises the internal gear α rotatably mounted on the center bearing J and is provided with the bearing sleeve b. Lugs c on the main driver project towards the drum drivers U and W and a pivot pin d transverse to the longitudinal axis of the machine carries the double ended pawl e between said lugs in such position that one end f or the other end g may rock into engagement with one set or the other of the teeth on the drum drivers U and W in accordance with the direction of rotation of the main driver so that one drum or the other is operatively connected to be driven by the main driver.

The main driving shaft D is provided

with the pinion *h* meshing with the intermediate gear *j* carried by the stub shaft *k* which is also provided with the pinion *o* meshing with the internal gear *a* forming the main driver. The reduction gearing *h*, *j*, and *o* is housed within the gear case *p* carried by the standard *B* and provided with the cover plate *q*. The drum flanges *r* and *s* may be provided with the brake bands *t* and *u* as desired.

I claim:

1. In a double drum hoist, the combination of a main driving shaft, two drums mounted side by side and rotatable relatively to the driving shaft, a reversible motor, a main driver connected to be rotated by the driving shaft at one end of the drums, drum drivers mounted at one end of the drums, and a double ended rocking pawl carried by the main driver on an axis transverse to the longitudinal axis of the hoist and automatically adjustable into engagement with one drum driver or the other

in accordance with the direction of rotation of the main driver.

2. In a double drum hoist, the combination of a main driving shaft, a reversible motor, two drums mounted side by side and rotatable relatively to the driving shaft, a main driver mounted at one end of the drums and connected to be driven by the driving shaft, concentrically arranged drum drivers carried by portions of said drums at one end, a double ended rocking pawl carried by the main driver and adjustable into engagement with one drum driver or the other in accordance with the direction of rotation of the main driver, said pawl being pivoted on an axis transverse to the longitudinal axis of the hoist, and said pawl extending in a plane including the plane of the longitudinal axis of the hoist.

In testimony whereof I have signed this specification.

EARL B. LEAR.
